PENHOLDER

Filed Nov. 6, 1926

FIG. 2.

FIG. 3.

Inventor

Charles T. Luthy

UNITED STATES PATENT OFFICE.

CHARLES T. LUTHY, OF PEORIA, ILLINOIS.

PENHOLDER.

Application filed November 6, 1926. Serial No. 147,292.

This invention has reference to new and improved features in the shapes of the stem and tip of the penholder, whereby its use will be simplified and improved and the learning 5 how to hold it facilitated and expedited.

In the drawings, the upper figure gives a view of the broad side of the stem, the middle figure of its edge, and the lower figure shows the penholder in its writing position.

10 Such features consist specifically: in the penholder having a stem that is flat—is thinner (1) from side to side than in the upward direction (2); in the stem having two, flat, or slightly rounded flat, sides that extend 15 from above where the first finger holds the side of the stem (3) down to below where the thumb holds the opposite side (4); in the stem having two, rounded edges (5), at right angles to its sides; and in the penholder having 20 a tip which is round (or as the curvature of the pen requires) for about the length of its socket and thence backward flattens to conform to the flat form of the stem (6) such tip being adjusted to one of such edges.

25 Such features effect the eleven improvements following:—First. Applicant's penholder, because of its flat shape, will not roll over or off the desk or table. The round penholder, because of its round shape, will do so.

30 Second. In applicant's penholder the flat sides and the adjustment of the tip to the edge that goes uppermost into the hand indicate how to pick up such penholder. The round penholder has not these indicating features.

35 Third. The flat sides and the adjustment of the tip to the edge that goes uppermost into the hand, in applicant's penholder, automatically enable one to place it into its proper 40 position in the hand. The round penholder always needs to have the pen point adjusted.

Fourth. Applicant's penholder, because of its flat shape, goes into the hand into a stable 45 position out of which it does not turn. The round penholder, because of its round shape, tends constantly to turn in the hand and its positioning must, therefore, be continually readjusted.

Fifth. As applicant's penholder, because 50 of its flat shape is not given to turn in the hand it is held only loosely, and as it is held by its flat sides this does not hurt the thumb and fingers. To prevent the round penholder from turning in the hand, such penholder is 55 held firmly and as it is held only by its peripheral edges, that hurts the thumb and fingers.

Sixth. As applicant's penholder is not given to turn out of its position in the hand, the writing tension can be relaxed during the brief intervals in writing, as on stopping to 60 think, on going back to read a line, on starting a new page, etc.; and that is restful. In the round penholder, if the writing tension is relaxed, the resuming such tension requires a readjustment of such penholder's position- 65 ing; and if such tension is not relaxed its continuance is straining and together with the firm holding tends to bring on writer's cramp.

Seventh. As applicant's penholder is held only loosely this does not hinder the action of 70 the fingers. In the round penholder, its firm holding so hinders such action as in many wholly to suppress it.

Eighth. As in applicant's penholder the thumb holds against a flat side the action 75 of the thumb does not tend to turn the penholder and as the opposite flat side bears against the side of the first finger this would prevent the turning. In the round penholder, as the thumb's edge holds against a peripheral 80 edge, and the thumb lies in a plane at right angles to the plane in which the first and second fingers lie, the action of the thumb tends to turn such penholder; and as the opposite peripheral edge rests against the side 85 of the first finger, this, instead of preventing the turning, as would applicant's flat side, facilitates it.

Ninth. As the finger action is unilinear— 90 moves only in the forward and back direction—and applicant's penholder owing to its flat shape and to being held by its flat sides, moves only in such unilinear direction, the child's practice with such penholder, because of such coincidence, will confirm correct 95 finger action into a habit. In the round penholder, owing to its constant tendency to turn, it is difficult to acquire such habit—many never acquire it.

Tenth. As the flat shape of applicant's penholder allows it to move only in the forward and back (the correct) direction, if there is a wrong tendency in the action of the child's fingers, as there often is, practice in such unilinear action with such penholder will overcome such erroneous tendency. In the round penholder, its constant disposition to turn is prone to confirm such erroneous tendency into 100 a habit.

Eleventh. As in applicant's penholder the 110 adjustment of the tip to one of the edges, the flat sides, and the holding of such penholder

by its flat sides cause the child automatically to place such penholder into its simple, easy, stable and movementally correct position in the hand, and to keep it so, such features will greatly simplify, facilitate and expedite the teaching and the learning how to hold and use such penholder. In the round penholder, its round shape presents such a complexity of difficulties, in such respects, that comparatively few learn to write well with the round penholder.

When it is considerad that, perhaps, the penholder next to the pencil is the most widely used instrument, and performs a delicate function, it can be seen that such perfect ad-

justment of such instrument to its delicate function is a great improvement.

Applicant claims as follows:—

A penholder having a stem that, when the penholder is in writing position, is thinner from side to side than in the upward direction, the stem having two flat or slightly rounded flat sides and two rounded edges at right angles to such sides; that has a tip that is round (or as the curvature of the pen requires) for about the length of its socket and thence backward flattens to conform to the flat form of the stem, the tip being adjusted to one of said two edges.

CHARLES T. LUTHY.
